IGNITION SHIELD DISCONNECT

Edward Medvetz, Carteret, N. J., assignor to
 Breeze Corporations, Inc., Newark, N. J., a
 corporation of New Jersey

Application April 24, 1946, Serial No. 664,676

1. Claim. (Cl. 174—91)

1 This invention relates to a disconnect for a radio shielded ignition system such as is used to permit the spark plug wires of an internal combustion engine to be readily connected to or disconnected from the rest of the ignition system.

The disconnect member in a shielded ignition system presents a potential failure point to the entire structure. It threatens an interruption in the continuous metallic covering of the ignition wires which would cause radio interference. It is also a point at which moisture may enter and thereby cause insulation failure.

The principal object of this invention, therefore, is to provide a disconnect which will be moistureproof and also a highly efficient radio shield.

A further object of this invention is a shielded disconnect which may be easily assembled and disassembled.

A feature of this invention is the small number of parts required.

Another object of this invention is to provide a flexible housing for the ignition wire within the disconnect to prevent the danger of breakage due to shocks or vibration.

A final object of this invention is to provide a disconnect which will maintain the ignition wire in a centrally located position well into the manifold outlet, preventing rubbing which might result in insulation damage.

The invention consists of the construction, combination and arrangement of parts, as herein described, illustrated and claimed:

In the accompanying drawings, forming part hereof, is illustrated one form of embodiment of the invention, in which drawings similar reference characters designate corresponding parts, and in which:

Figure 1 is a longitudinal section of a complete embodiment of the shielded disconnect as it appears in actual use.

Figure 2 is a vertical section on line 2—2 of Figure 1.

Figure 3 is a vertical section on line 3—3 of Figure 1.

Figure 4 is a longitudinal section of the rubber sleeve shown in Figure 1.

Referring to the drawings, and particularly to Figure 1, 10 indicates a flared manifold outlet such as is soldered to the manifold in the well known manner. A bushing 11 is soldered or otherwise attached to the end of the outlet 10. Said bushing 11 is provided with external threads 12 and an internal bore 13.

A rubber sleeve 14, shown in detail in Figure 4,

2 is inserted in the bore 13 in such manner that a rearward extension 15 thereof projects well within the manifold outlet 10. A rubber wall 16 integral with said sleeve and having a central bore 17 therein is spaced from the end of the sleeve opposite the outlet 10. The portion of the sleeve 14 which seats in the bushing bore 13 is enlarged and accommodates an annular groove 18 which is used for a purpose hereinafter described. A central bore 19 completes the construction of the sleeve 14.

The stranded ignition cable 20 is passed through the bore 19 in the sleeve 14. The insulation 20a is stripped from the end of the cable and the strands 21 divided, half being passed through each of two holes 23 in a metal terminal sleeve 22. (See Figure 2.) Both holes 23 lead into the sleeve bore 24 where the wires 21 are twisted together again. This holds the metal terminal sleeve 22 in firm contact with the rubber sleeve 14 and positioned within the socket 25 formed by the bore of the rubber sleeve 14 and the rubber wall 16.

The small end of a contact spring 26 is now forced over the outside diameter of the metal terminal sleeve 22 until the end turn of the spring 26 snaps into a groove 27 in the said sleeve. This secures the spring 26 in position.

A dielectric sleeve 28 is next urged over the assembled rubber sleeve 14 until its thinned edge 29 seats itself within the annular groove 18 in the said rubber sleeve 14. The outer metal shield 30 is slipped over the dielectric sleeve 28 and rotated. The shield 30 is internally threaded at 31 and engages the thread 12 on the bushing 11 as it is rotated. An external thread 32 is provided on the opposite end of the shield 30 for a purpose which will be described below. An internal shoulder 33 machined in the shield 30 forces the dielectric sleeve 28 against the rubber sleeve 14 and holds the said sleeve 28 in place. The rubber of the sleeve 14 is also compressed by the attachment of the shield 30, thereby forming a sealed joint around the cable 20 and in the vicinity of the juncture of the shield 30 and bushing 11. (See Figure 3.)

The opposite terminal of the disconnect is assembled by slipping a coupling nut 34 over the shielded conduit 35 and soldering a ferrule 36 to the end of the conduit 35 in the well known way. The cable 20 is then stripped at its end to expose the stranded ignition wire 21. A yielding rubber sleeve 37 is then passed over the cable. Said sleeve 37 has a wall 38 spaced from its end and identical in construction to the above-mentioned wall

18. A collar 48 formed on the outer end of the sleeve 37 completes its construction. The wire strands 21 are drawn through the bore in the wall 38 and separated into two groups. The strands are next passed through the two holes in a button shaped metal terminal 39. The wires are then twisted together to secure the terminal 39 to the sleeve 37.

When the coupling nut 34 is rotated, it engages the external threads 32 of the shield 30. This forces the rubber sleeve 31 forward within the dielectric sleeve 28 until the spring contact 26 bears against the metal terminal 39, completing the electrical connection. The shielding connection is completed when the coupling nut 34 is tightened. The rubber collar 40 is also compressed as the coupling nut 34 is tightened. This forms a sealed joint around the cable 20 and at the juncture of the ferrule 36 and shield 30.

By referring to Figure 4 it can be seen that the 20 rearward extension 15 of the rubber sleeve 14, which extends into the manifold outlet 10, is provided with a collar 41 integral with said sleeve 14. The function of this collar 41 is to prevent the cable 20 from rubbing against the outlet 10 when in use. It is apparent that such friction would result in a breakdown of the cable insulation and a consequent failure of the shielded ignition system.

While the dielectric mentioned throughout this 30 specification has been referred to as rubber, it is apparent that any other compressible dielectric may be used.

Having thus fully described the invention, what is claimed as new and desired to be secured by 35 Letters Patent of the United States, is:

A radio shielding electric disconnect comprising a flexible dielectric sleeve to receive an insulated conductor, a shoulder and spaced surrounding skirt formed on said sleeve, a second opposed dielectric sleeve to receive a second insulated conductor, means intermediate of the said sleeves to establish electrical connection between the conductors, a third dielectric sleeve to overlie both first mentioned sleeves, a reduced extension on said third sleeve to enter the space between the first mentioned sleeve and its surrounding skirt, a metal coupling member secured around said skirt, a metal sleeve to surround the major portion of the aforementioned dielectric sleeves and to engage the coupling member to form a liquid tight seal, and a second coupling member on the opposite end of the metal sleeve to force the flexible parts together to insure a liquid tight seal.
